UNITED STATES PATENT OFFICE.

AUGUSTUS STUDDIFORD, OF LIBERTY, NEW YORK.

PHOTOGRAPHIC WASHING APPARATUS.

SPECIFICATION forming part of Letters Patent No. 633,922, dated September 26, 1899.

Application filed December 13, 1898. Serial No. 699,139. (No model.)

To all whom it may concern:

Be it known that I, AUGUSTUS STUDDIFORD, of Liberty, in the county of Sullivan and State of New York, have invented a new and Improved Washing Apparatus, of which the following is a full, clear, and exact description.

The object of the invention is to provide a new and improved washing apparatus, more especially designed for the use of photographers and amateurs and other persons, to enable them to wash photographic negatives and prints in an effective, thorough, and automatic manner.

The invention consists of novel features and parts and combinations of the same, as will be fully described hereinafter and then pointed out in the claims.

Reference is to be had to the accompanying drawings, forming a part of this specification, in which similar characters of reference indicate corresponding parts in all the views.

Figure 1 is a sectional side elevation of the improvement on the line 1 1 in Fig. 2. Fig. 2 is a plan view of the same with part in section on the line 2 2 in Fig. 1, and Fig. 3 is a perspective view of the rack for holding the plates.

The improved apparatus is provided with a tank A, mounted on suitable legs B and provided in its bottom with a step C, on which is mounted to turn the hub D' of a wheel D, having a disk D² on the top of the hub, and a ring D³ concentric to the disk D² and connected by wings D⁴ with the hub D', as is plainly illustrated in the drawings.

On the top of the ring D³ are secured a series of posts E for preventing the trays F from moving while stacked on the top of the wheel D, each tray being provided with a rectangular frame F' and a wire-netting F², secured to the frame and covering the opening thereof. On the corners of the frame F' are arranged upwardly-extending flanges F³, on which the next following tray is set, so that the several trays have their wire-netting bottoms spaced apart, as will be readily understood by reference to Fig. 1.

On one side of the tank A, which is preferably cylindrical, is arranged a well A', the bottom of which is somewhat lower than the bottom of the tank, and in this well A' extends the lower end of a water-supply pipe

H, connected with a suitable water-supply and provided at its lower end with a horizontally-disposed nozzle H', extending in a tangential direction to the wheel D under the ring D³, so as to deliver the water under pressure against the wings D⁴ to rotate the wheel in the tank A, and with it the trays F containing the films or prints to be washed. In the well A' is also arranged a siphon J, the long leg of which extends through the bottom of the well, the lower end of the short leg extending to the level of the bottom of the tank A, as indicated in Fig. 1. The bend or upper portion of the siphon is a short distance below the top of the tank.

When the trays F are filled with negatives or films and water is permitted to flow through the pipe H, then the stream of water issuing through the nozzle H' and impinging on the wings D⁴ causes the wheel D to rotate, and with it the trays containing the prints or films. As the water accumulates in the tank A it fills the trays, and consequently washes the prints or films while the trays and films are in motion. Thus it will be seen that a very thorough and effective washing of the prints or films is assured without requiring special manipulation of the trays by the operator.

When the water has nearly filled the tank A, it automatically sets the siphon J in action, so that the water is quickly drawn out of the tank A, especially as the supply is comparatively small relatively to the discharge of the water from the tank to the siphon.

In order to keep the prints or films moist during the time the tank A is being refilled through the supply H and nozzle H', I provide a rose or sprinkler I, secured on a branch pipe I', connected with the supply-pipe H, and this rose or sprinkler I is arranged over the tank in an angular position to cause the water to be sprayed over the entire surface of the uppermost tray, through which the water can flow to the other trays below to keep the prints and films moist while the tank A refills with water, as before mentioned.

In case it is desired to wash negative-plates I dispense with the trays F and employ a rack G, made in the shape of a rectangular frame G', supported on a skeleton box G², as is plainly shown in Fig. 3. The sides of the

frame G are corrugated at their inner faces, as indicated at G³, to hold the plates securely in position in the rack and to hold the plates spaced apart to permit the water to readily pass to the sensitive coating of the plates.

The tray G, with the plates held therein, is set on the wheel D between the posts E, and the rack, with the plates therein, turns with the wheel the same as the trays, the washing 10 taking place in precisely the same manner as above described relatively to the films and prints.

In order to render the trays useful for smaller prints, I provide thin cross-shaped frames K, adapted to rest on top of the trays, with slots in the frame-bars to carry short lugs or stops for holding the plates or prints in position. Thus, as shown, four small prints 15 can be accommodated in one tray. The tank, the revolving wheel, and the negative-rack are preferably provided with suitable handles.

Having thus fully described my invention, I claim as new and desire to secure by Letters Patent—

25 1. A washing apparatus for the purpose described, comprising a tank having a water-supply, a wheel mounted to turn about a vertical axis in said tank and adapted to be driven by the water-supply, a series of posts extending vertically from the upper surface of said wheel and a tray on the said wheel between the posts and held thereon by said posts when the wheel is turned as set forth.

30 2. A washing apparatus for the purpose de-

scribed comprising a tank, a wheel mounted 35 to turn about a vertical axis in said tank and provided with a series of posts extending vertically from its upper face, and superposed trays supported on said wheel between said posts, the said trays being formed with a rectangular frame, a reticulated bottom in said frame, and upturned flanges on said frame whereby the bottom of each tray is spaced from the bottoms of the adjacent trays, as set forth.

45 3. In a washing apparatus for the purpose described, the combination of a tank formed with a well, a tray-carrying wheel mounted in said tank, a siphon in said well, and a supply-pipe extending down into said well, said pipe being provided at its end with a nozzle adapted to throw a jet against the wheel to rotate the same and a branch pipe above the nozzle and in the upper part of the tank, the said latter pipe being provided with a sprinker whereby to spray the trays while the tank refills after being emptied by the siphon, as set forth.

50 4. A washing apparatus, provided with a tray having a rectangular frame, a wire-netting covering the opening in said frame, and upturned flanges on said frame, substantially as shown and described.
